Primary Examiner—Brian N. Vinson**Attorney, Agent, or Firm**—Peter K. Kontler**[57]****CLAIM**

The ornamental design for a dispenser for liquid soap, as shown and described.

DESCRIPTION

FIG. 1 is a top, front, and right side perspective view of a dispenser for liquid soap showing my new design; FIG. 2 is a front elevational view thereof; FIG. 3 is a left-hand side elevational view thereof; FIG. 4 is a rear elevational view thereof; FIG. 5 is a top plan view thereof; and, FIG. 6 is a bottom plan view thereof. The right-hand side is a mirror image of the left-hand side of the dispenser.

FIG. 1

FIG. 2

FIG. 3

FIG. 4

FIG. 5

FIG. 6
